[57] CLAIM

The ornamental design for a combined hoisting platform and control console therefor, as shown and described.

DESCRIPTION

FIG. 1 is a front perspective view of a combined hoisting platform and control console therefor showing my new design;

FIG. 2 is an opposite side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged perspective view of the control console shown on the left side of FIG. 1; and,

FIG. 10 is an enlarged perspective view of the control console shown on the right of FIG. 1.
